UNITED STATES PATENT OFFICE.

JACOB S. JAMMER, OF NEW YORK, N. Y., ASSIGNOR TO WESTERN ELECTRIC COMPANY, INCORPORATED, OF NEW YORK, N. Y., A CORPORATION OF NEW YORK.

CURRENT-WAVE REPEATER.

Application filed September 19, 1919. Serial No. 824,876.

To all whom it may concern:

Be it known that I, JACOB S. JAMMER, a citizen of the United States, residing at New York, in the county of New York, State of New York, have invented certain new and useful Improvements in Current-Wave Repeaters, of which the following is a full, clear, concise, and exact description.

The present invention relates to current wave amplification and particularly to two-way repeating means for current waves. A feature of the invention is the use of a single amplifying element for simultaneously repeating waves in both directions.

It is customary in two-way repeating of current waves to divide the transmission line into two sections and to provide a separate amplifying path for transmission in each direction between said sections. In this way the energy received from a line section is amplified and passed on to a different section rather than being merely reapplied to the same line. In case the transmissions in one direction all differ from those in the other direction in some characteristic such as the frequency, it is possible by the use of a single amplifier, according to the present invention, to receive energy from one line section, amplify it, and to apply it practically exclusively to another line section.

In the drawing Figs. 1 and 3 are schematic diagrams of circuits adapted for two-way repeating of separate single frequencies, for instance, in a carrier wave telegraph system, and Figs. 2 and 4 show arrangements that may be used for repeating separate frequency ranges such as are met with in telephony.

In Fig. 1 the line sections between which two-way repeating is to be accomplished are indicated as 1 and 2. These may be multiplex carrier telegraph lines which carry a plurality of separate frequencies forming individual communication channels or they may be lines for other uses. Transmission to the right in the figure is effected by frequencies C_1 , C_2 , C_4 which may be the usual carrier frequencies while frequencies C_1 , C_3 and C_5 are used for transmission to the left. The frequencies used for transmission in one direction are preferably intermediate those used for transmission in the opposite direction in accordance with the well-known staggered frequency carrier wave systems although such an arrangement of the frequencies is not necessary, but the present inven-

tion requires simply that the frequencies used in one direction be different from those used for the opposite direction. Although only three frequencies are indicated for each direction there could of course be any desired 60 number. Nets 3 and 4 respectively, are provided for balancing the lines 1 and 2 for the transmitted frequencies and the usual conjugate coils 5, 6, 9 and 7, 8, 10 enable waves to be received from and applied to each of 65 the respective lines without mutual interference. A single amplifier 11 of any suitable type serves to repeat all the transmitted waves simultaneously in both directions between the line sections 1 and 2. For this 70 purpose its input path 12 is related to both line sections in common and its output path 13 is related to the two line sections through respective filters 14, 15, 16 and 17, 18, 19. The filters shown in Figs. 1 and 2 are band 75 filters, preferably of the general type disclosed in the patent to G. A. Campbell, No. 1,227,113 granted May 22, 1917. Filters 14, 15 and 16 are so designed as to pass only the frequencies that are repeated from line 80 section 2 to line section 1, i.e., C_1 , C_3 and C_5 , while the filters 17, 18 and 19 pass only the frequencies C_1 , C_2 and C_4 that are repeated from line section 1 to line section 2. By this provision a wave of frequency C_1 , for instance, received from line section 1 is transmitted through the couplings 9 and 12, is amplified by amplifier 11, is impressed through coupling 13 and the filter 17 to the line section 2, but is prevented from being 85 reapplied to the line section 1 by the filters 14, 15 and 16 each of which highly attenuates and substantially extinguishes current of frequency C_1 .

In similar manner, waves of frequencies 90 C_2 and C_4 are selectively impressed upon line section 2 in amplified form through filters 18 and 19 respectively and waves of frequencies C_1 , C_3 and C_5 are amplified and selectively impressed upon line section 1, through filters 14, 15, 16 respectively. The amplified waves delivered to line section 2, for instance, are prevented from passing again to the input side of the amplifier by virtue of the well-known balanced arrangement of the coils 7, 8 and 10.

It should be noted that this invention is particularly adapted to systems in which the frequencies transmitted in one direction are all above those that are transmitted in 110

the opposite direction in which case only an upper limiting and a lower limiting filter would be needed in the output circuit of the amplifier. These two filters would serve to separate all the frequencies transmitted in one direction from those transmitted in the opposite direction.

The band filters shown in Fig. 1 may be used to pass more than the frequencies used in a single transmission channel. For instance, each filter 17, 18, 19, may pass a group of telegraph-controlled carrier waves, and the filters 14, 15 and 16 may each also pass a group of similar waves which latter groups comprise frequencies respectively intermediate those of the other groups of waves. This might be the case, for instance, where each of several stations on the main line 1, 2, utilizes a different group of frequencies for each direction of transmission.

In case the waves to be repeated in either direction comprise substantially single frequencies which are to be separately impressed on the respective line sections 1, 2, the band filters of Fig. 1 would be replaced by the simple tuned circuits such as are shown in Fig. 3. Such circuits would be used in carrier telegraphy where the separate single frequencies used for transmitting in the two directions are staggered, for instance. In Fig. 3, only the line section 2 and the selective circuits for repeating into it are illustrated. The output multiplex wave from the amplifier through the coupling 13 is impressed upon a number of selective circuits such as 32 and 33, there being one such circuit for each frequency transmitted. The tuned circuits 32 and 33 on the right of the connections of transformer 13, are selective of those frequencies which are to be impressed on line section 2 and there would, of course, be other selective circuits on the left (but they are not shown), for selecting the frequencies to be transmitted to the line section 1. The respective tuned circuits 32, 33, etc., are coupled to corresponding tuned circuits 34, 35, etc., which are bridged across the line section 2, for conveying the amplified currents to the line. The circuit of Fig. 2 is arranged for repeating carrier waves that are modulated in accordance with a range of frequencies, for example by voice frequencies. In Patent No. 1,454,495, to H. J. Vennes, May 8, 1923, a system is disclosed in which the same carrier frequency is used for transmission in both directions, but the signaling frequencies for the opposite directions are staggered. This effect is obtained by transmitting in one direction a given side band, the upper band, for example, obtained by modulating the carrier by the voice, and transmitting the opposite band, in this case the lower, in the other direction. The arrangement of Fig. 2 is adapted for such a system. Transmission to the right may be affected by use of the upper bands C+S, for instance, where C denotes a carrier frequency and S a range of signaling frequencies, for example, voice frequencies. There are, of course, in practice, several carrier frequencies and it is convenient to have the corresponding side band of each modulated carrier wave, the upper bands, for instance, all transmitted in the same direction although this is not necessary.

Similarly, transmission to the left is effected by use of the lower bands designated in the drawings as C-S. The connections of Fig. 2 are substantially the same as those in Fig. 1, but a modification is made in the amplifier and the constants of the filters are of course, arranged to take care of the particular frequency bands transmitted. Amplifier 20 is preferably of the push-pull type consisting of the two thermionic amplifiers 21 and 22 connected oppositely as to their common output and input sides. Such an amplifier by virtue of its straight line characteristic is especially adapted to amplify over a large frequency range without distortion or inter-modulation of the various waves. Waves incoming from line 1 are amplified by amplifier 20 and impressed on the output circuit connected to both line sections. Only the filters 24 to 27, however, are adapted to pass the upper bands of the several carrier frequencies, and it is only on line section 2, therefore, that these bands are impressed. For transmission in the opposite direction, the filters 28 to 31 are provided to pass the lower bands of the several carrier frequencies.

While the means for repeating telephonic messages has been described in connection with a system in which the signaling frequencies are staggered, it is equally adapted to a system in which the carrier frequencies are staggered. For instance, the carrier waves indicated in Fig. 1 may each be modulated by voice frequency waves and an amplifier similar to 20 and the appropriate filters may be inserted in place of those illustrated in Fig. 1 to take care of the frequency ranges that are transmitted.

In either arrangement shown the path of the repeated waves could be made still more selective, of course, by placing other filters in the input of the repeater. An arrangement of this kind suitable for use with the system of Fig. 2 is shown in Fig. 4 where the C+S filters 32 to 35 are connected between the coil 9 associated with the line section 1 and the transformer 12 and where the C-S filters 36 to 39 are connected between the coil 10 associated with line section 2 and the same transformer 12. A similar arrangement could be used with the system of Fig. 1, the only difference being in the constants of the filters which are necessarily

adapted to take care of the particular frequencies to be transmitted. In view of the description of the operation of the filters 24 to 31 hereinbefore given, the operation of filters 32 to 39 is obvious and further detailed description is therefore unnecessary. It is obvious that in the arrangement in which filters are employed in both the input and output circuits of the repeater, the filters by their selective action prevent "singing" and so duplicate the functions of the nets and conjugate coils.

The invention is not to be limited to the particular filters illustrated nor to their exact mode of connection in the circuit. Also the invention is not to be limited to a single stage amplifier since a two or more stage amplifier could be used if desired and the term "single amplifier" as used in the claims is not to be understood as restricting the number of stages of amplification used. The amplifier likewise need not be the particular type shown nor is the invention to be otherwise limited by the specific embodiment which has been shown, but only by the scope of the appended claims.

What is claimed is:

1. A line for transmitting a plurality of current waves in each direction, each of substantially different frequency from all the others, a second similar line, a single amplifying circuit having its input side connected to both of said lines and its output side connected to both of said lines, and means for maintaining the output connection of the amplifier to each line substantially conjugate with respect to the input connection of the amplifier to the same line.

2. A line for transmitting a current wave in each direction, each wave modulated in accordance with signals, a second similar line, a single amplifying circuit having its input side connected to both of said lines and its output side connected to both of said lines, and balancing networks for maintaining the output connection of the amplifier to each line substantially conjugate with respect to the input connection of the amplifier to the same line.

3. Two lines, an amplifier for said lines, a selective path from the first said line through said amplifier to the other line, and another selective path from said other line through said amplifier to said first line.

4. Two lines, and an amplifier having an input circuit coupled to both of said lines, and an output circuit coupled to one of said lines through a selective path and to the other line through a selective path having different characteristics.

5. Two lines, and means including selective paths and a single amplifier for simultaneously amplifying the energy on one line and impressing it on the other line and for amplifying the energy on said other line

and impressing it on the first line without mutual interference.

6. A line for transmitting a plurality of frequencies in one direction and a plurality of different frequencies in the other direction, a second similar line, an amplifier for amplifying all of said frequencies simultaneously, and selective means for confining each said plurality of frequencies to the respective direction for transmission between said lines.

7. Two lines for conveying a plurality of substantially different frequencies in each direction, and two-way repeating means between said lines for all said frequencies, said means comprising a single amplifier and selective paths for said frequencies.

8. Two lines for the transmission of current waves in both directions, the waves transmitted in one direction having a different characteristic from those transmitted in the other direction, a one-way selective path between said lines for the waves transmitted in one direction, another one-way selective path between said lines for the waves transmitted in the opposite direction, and a single amplifier common to both said paths.

9. Two lines for the transmission of current waves in each direction thereover, the waves transmitted in one direction having respectively different characteristics from those transmitted in the opposite direction, an amplifier for amplifying all of said waves having its input and its output circuits each common to both of said lines, and a plurality of selective paths in said output circuit between said amplifier and each of said lines for selectively transmitting said waves.

10. Two lines for the transmission of current waves in each direction thereover, the waves transmitted in one direction having respectively different characteristics from those transmitted in the opposite direction, an amplifier for all of said waves having an input circuit common to both lines, and an output circuit having two branches one for each line and filters having different characteristics in each of said branches.

11. A high frequency channel for two-way communication in which wave components of a given high frequency plus signal frequency are transmitted in one direction and wave components of said high frequency minus signal frequency are transmitted in the opposite direction, said channel being divided into two sections, a repeater for repeating all said wave components between said sections comprising a single amplifier having an input circuit common to said sections, an output circuit common to said sections, and filters for confining the sum frequencies to transmission in one direction between said sections and the difference frequencies to transmission in the opposite direction.

- 4
12. A line for transmitting a wave in one direction and a wave having a different characteristic in the opposite direction, said line being divided into two sections, an amplifier between said line sections for amplifying both of said waves, and circuits associated with said amplifier selective of the respective waves for causing the wave received over each line section to be transmitted only over the other line section. 30
13. A line for transmitting current waves of respectively different frequencies in both directions, said line being divided into two sections, a balancing circuit for each section and a conjugate connection for each section having input and output terminals which are mutually neutral with respect to each other, an amplifier having input and output circuits, the said output terminals of each line section being connected with the input circuit of said amplifier, and connections between the output circuit of said amplifier and the input terminals of each line section, said connections including selective 35 means for causing the waves in coming from each line section to be impressed only on the other line section. 40
14. Two lines for the transmission of current waves in each direction thereover, the 45
5. waves transmitted in one direction having respectively different characteristics from those transmitted in the opposite direction, an amplifier for all of said waves, an input circuit and an output circuit for said amplifier, each having two branches one for each line, and filters in each of said branches. 50
10. 15. A high frequency channel for two-way communication in which wave components of a given high frequency plus signal frequency are transmitted in one direction and wave components of said high frequency minus signal frequency are transmitted in the opposite direction, said channel being divided into two sections, a repeater for repeating all of said wave components between said sections comprising a single amplifier having an input circuit common to said sections and an output circuit common to said sections, and filters in both said input and output circuits for confining the sum frequencies to transmission in one direction between said sections and the difference frequencies to transmission in the opposite direction. 55

In witness whereof, I hereunto subscribe my name this 15th day of September A. D., 1919.

JACOB S. JAMMER.
